LOCK DISPLAY STAND

Adolf Schoepe, Anaheim, Calif.

Application April 2, 1949, Serial No. 1,782

Term of patent 14 years

(Cl. D80—9)

To all whom it may concern:

Be it known that I, Adolf Schoepe, a citizen of the United States, residing at Anaheim, in the county of Orange and State of California, have invented a new, original, and ornamental Design for a Lock Display Stand, of which the following is a specification, reference being had to the accompanying drawing, forming part thereof:

Fig. 1 is a perspective view of a lock display stand showing my new design;

Fig. 2 is a side elevational view;

Fig. 3 is a top plan view;

Fig. 4 is a rear elevational view; and

Fig. 5 is a vertical section taken substantially upon the line 5—5 upon Fig. 2 in the direction indicated.

The broken lines are shown for illustrative purposes only.

I claim:

The ornamental design for a lock display stand, as shown and described.

ADOLPH SCHOEPE.
